US00D777227S

(12) **United States Design Patent** (10) **Patent No.:** **US D777,227 S**
Kao et al. (45) **Date of Patent:** **** Jan. 24, 2017**

(54) **STEREOLITHOGRAPHY MACHINE**

(71) Applicants: **XYZPRINTING, INC.**, New Taipei (TW); **KINPO ELECTRONICS, INC.**, New Taipei (TW); **CAL-COMP ELECTRONICS & COMMUNICATIONS COMPANY LIMITED**, New Taipei (TW)

(72) Inventors: **Chieh Kao**, New Taipei (TW); **Wen-Chun Chung**, New Taipei (TW); **Chun-An Hsu**, New Taipei (TW)

(73) Assignees: **XYZPRINTING, INC.**, New Taipei (TW); **KINPO ELECTRONICS, INC.**, New Taipei (TW); **CAL-COMP ELECTRONICS & COMMUNICATIONS COMPANY LIMITED**, New Taipei (TW)

(**) Term: **15 Years**

(21) Appl. No.: **29/550,570**

(22) Filed: **Jan. 5, 2016**

(51) LOC (10) Cl. **15-09**

(52) U.S. Cl.

USPC **D15/122; D15/135**

(58) **Field of Classification Search**

USPC D15/122, 135, 138, 145, 146; D18/6-7, D18/14, 19, 50, 54, 54.1, 55, 59

See application file for complete search history.

(57) **CLAIM**

The ornamental design for a stereolithography machine, as shown and described.

DESCRIPTION

FIG. 1 is a perspective view of a stereolithography machine showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown represent unclaimed environmental subject matter.

1 Claim, 7 Drawing Sheets
